Primary Examiner — Vy N Koenig(74) Attorney, Agent, or Firm — Kreative IP Management LLC; Fuiyeong Kim(57) CLAIM

The ornamental design for a lipstick as shown and described.

DESCRIPTION

FIG. 1 is a perspective view of a lipstick showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines depict portions of the lipstick that form no part of claimed design.
